UNITED STATES PATENT OFFICE

RUSSELL T. SMITH, OF GREENVILLE, MICHIGAN

DESIGN FOR A REFRIGERATOR CABINET

Application filed March 23, 1931. Serial No. 39,216. Term of patent 7 years.

To all whom it may concern:

Be it known that RUSSELL T. SMITH, citizen of the United States, residing at Greenville, county of Montcalm, State of Michigan, has invented a new and ornamental Design for Refrigerator Cabinet, of which the following is a specification, the accompanying drawings forming part thereof.

Figs. 1, 2 and 3 are respectively, front, top, and side views of the refrigerator cabinet showing my new design.

What I claim is:

The ornamental design for a refrigerator cabinet, substantially as shown.

In testimony whereof, I sign this specification.

RUSSELL T. SMITH.
